UNITED STATES PATENT OFFICE.

CHARLES EDWARD HAVILAND, OF LIMOGES, FRANCE.

DESIGN FOR A COVERED DISH OR SIMILAR ARTICLE.

SPECIFICATION forming part of Design No. 35,783, dated March 4, 1902.

Application filed February 3, 1902. Serial No. 92,479. Term of patent 7 years.

To all whom it may concern:

Be it known that I, CHARLES EDWARD HAVILAND, a citizen of the United States, residing at Limoges, in the Republic of France, have 5 invented and produced a new and original Design for a Covered Dish or Similar Article, of which the following is a specification, reference being had to the accompanying drawings, forming a part thereof, and in which—

10 Figure 1 is a top elevation of a covered dish bearing and incorporating my design. Fig. 2 is a side elevation of same, and Fig. 3 is a vertical section through a portion of same on the dotted line 3 3 of Fig. 1.

15 The leading feature of my design consists of the shape and configuration of the covered dish, substantially as shown.

In the drawings, A designates the body of the dish, and B the cover therefor. The cover 20 B has the raised central portion C outlined by the ornate scalloped scroll D and bearing the ornate handle E. The outer edges of the cover B are scalloped and bear at equidistant points the ornate scroll-figures F. The sides 25 of the body A are of ornate configuration and

comprise the upper section G and lower section H, the latter being scalloped and merging on graceful lines into the base I. The upper section of the body A affords the effect of a broad band J, extending around said body 30 and scalloped at its upper and lower edges, as denoted at K L, respectively, the said band J being also scalloped vertically, as at M. The band J at equidistant points along its upper scalloped edge bears the ornate scroll- 35 figures N, harmonizing with the figures F on the cover B, and along its lower scalloped edge the band J bears the ornate scroll O, harmonizing with the scroll-outline D on said cover B. At the opposite ends of the body A 40 are the handles P.

What I claim is—

The design for a covered dish, substantially as shown and described.

Signed at Limoges, in the Republic of 45 France, this 20th day of January, A. D. 1902.

CHARLES EDWARD HAVILAND.
